No. 14,460

Nov 27, 1883

UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A LADY'S BASQUE.

SPECIFICATION forming part of Design No. 14,460, dated November 27, 1883.

Application filed September 26, 1883. Term of patent 3½ years.

To all whom it may concern:

Be it known that I, LOUISE TULLY, of the city, county, and State of New York, have invented and produced a new and original Design for a Pattern of a Lady's Basque, (numbered 8,897;) and I do hereby declare that the engraved prints accompanying this specification convey to any one accustomed to using paper patterns a clear understanding of how a garment made up by the pattern will appear.

The design shows a closely-fitted back with closely-fitted fronts, which latter are buttoned all the way down and partly covered by shorter

over-jacket fronts, closely fitted and curved away from the tops of the shoulders, being deep and of uniform outline all the way around, and exhibiting coat-sleeves and a standing collar.

What I claim as my invention, and desire to secure by Letters Patent, is—

The design for a lady's basque, as shown in the engraved prints accompanying this specification.

LOUISE TULLY.
